TEXTILE FABRIC

Robert Finkelstein, Woonsocket, R. I., assignor to Jacob Finkelstein & Sons, Woonsocket, R. I., a partnership

Application April 11, 1955, Serial No. 35,464

Term of patent 7 years

(Cl. D92—1)

This figure is a plan view of a textile fabric showing my new design. The design unit is contained within the dot-and-dash lines, which unit is repeated in regular succession, as indicated by the extensions beyond the unit boundaries.

I claim:

The ornamental design for a textile fabric, as shown and described.
